UNITED STATES PATENT OFFICE.

LESLIE H. NASH, OF NEW YORK, N. Y.

DESIGN FOR A LAMP-SHADE.

44,731.

Specification for Design.

Patented Oct. 14, 1913.

Application filed July 24, 1913. Serial No. 781,032. Term of patent 3½ years.

To all whom it may concern:

Be it known that I, LESLIE H. NASH, a citizen of the United States, and a resident of the city of New York, Flushing, borough of Queens, in the county of Queens and State of New York, have invented a new, original, and ornamental Design for a Lamp-Shade, of which the following is a specification, reference being had to the accompanying drawing, forming part thereof.

The figure is a perspective view of a lamp shade showing my design.

I claim:

The ornamental design for a lamp shade as shown.

LESLIE H. NASH.

Witnesses:
